LIGHTER

Leslie D. Jamieson, Toronto, Ontario, Canada

Application March 19, 1940, Serial No. 324,802
In Canada June 7, 1939

2 Claims. (Cl. 219—32)

My invention relates to a combined advertising and cigarette, cigar and pipe lighting device.

The objects of the invention, generally, are to provide a device adapted to display advertising media while having means for lighting cigarettes, and/or cigars, and/or pipes. Such a device may also be adapted to display actual wares, either in addition, or not, to carrying advertising media.

A specific object of the invention is to so design the device that it will be of simple and sturdy construction, easily opened to gain access thereto as for purposes of repairs or changing the advertising media, or in the case of a device actually storing and displaying wares, to remove or change the wares.

Another specific object of the invention is to provide a very efficient lighter for pipes, the lighter having a shiftable baffle plate adapted to be engaged by the rim or upper edge of the pipe bowl.

Another specific object of the invention, in one form thereof, is to provide hinged doors or members adapted to open and allow access to the lighter proper, and to close and shield the same, by the operation of the lighter switch button.

Still another specific object of the invention is to provide a specially designed, and very efficient, lighter proper.

Other objects and advantages of the invention may be seen by a perusal of the specification to follow, in the light of the drawings.

In the drawings, wherein like numerals of reference indicate corresponding parts in the various figures,

Figure 1 is a front elevation of the device, parts being broken away;

Figure 2 is a longitudinal section of the device, on approximately line 2—2 in Figure 1;

Figure 3 is a fragmentary, part-section, part-elevation, front view of the device, showing a modified form of cover;

Figure 4 is a fragmentary rear elevation view of the rear plate of the casing of the device, showing a modified form of rear plate;

Figure 5 is a section on line 5—5 in Figure 4;

Figure 6 is a front elevation of the lighter;

Figure 7 is a longitudinal section of the electric element of the lighter, parts being shown in section;

Figure 8 is a fragmentary view of the element, showing a modified form thereof;

Figure 9 is a similar view to Figure 8, but showing another modified form of the element;

Figure 10 is a fragmentary view of Figure 2, on an enlarged scale, showing switch and actu-

ating push button partly in section and partly in elevation;

Figure 11 is a view similar to Figure 10, but showing a modification of casing cover and switch, and showing hinged doors;

Figure 12 is a section on line 12—12 in Figure 11.

Referring now by numerals to the drawings, 10 is a casing, taking the form of an ornamental cabinet, preferably comprising a rear or base plate or member 11 and a removable front member or cover 12. The base plate 11 is adapted to be secured, say, as with screws (not shown) to a wall or other fixed part of a building. The cover 12 is formed with a centre opening 13 which, as shown, is closed by a glass panel 14, on which is applied the desired advertising medium. The advertising medium may, if desired, be applied to a separate member, such as 15 an iron plate, cardboard, glass panel, or other, and this separate member suitably applied behind the glass panel; or again, this separate member may be placed between the glass panel 14 and a second glass panel placed behind the 20 first or outside glass panel.

In order to conveniently apply the cover 12 to the rear or base plate 11, the upper portion of the base plate is provided with lugs or hooks 16 adapted to removably receive suitably-formed 25 downwardly-extending lugs 17 from the cover 12. The lower end of the cover may be held in closed position on the rear plate, as with screws 18 threaded into the rear plate, and/or by means of a suitable key lock or catch of suitable design 30 (not shown).

To provide illumination behind the glass panel 14, two electric bulbs 20, of elongated or tubular form of any well-known make, may be provided as shown. The bulbs rest between end members 35 or sockets 21 which extend laterally to rest on, and be secured to lugs 22 extending forwardly from the rear plate 11.

In order to dissipate the heat generated by the electric bulbs, the upper portion of the cover 12 40 may be provided with slots or openings 25, while the lower portion of the cover may be formed with apertures 26 formed through the bottom wall 27. The heated air within the device will thus pass out through the slots or vents 25, while cool air will pass up through the apertures or 45 vents 26.

Where the device is installed outside of a building, or is otherwise exposed to the elements, either the cover, or the rear plate, may be slightly 50 modified, as shown in Figures 3, and 4 and 5, re-

spectively. For instance, the upper portion of the cover, 12A, may be formed with a centre or dome portion 29, open at the top as at 30 and having its end walls 35 partly open as at 31. Within the dome are superposed, spaced and staggered plates 32 and a top plate 33, all of which extend between and are integral with parallel walls of the dome, and are so arranged as to shed any rain falling through the top opening 30. Alternatively, and as shown in Figures 4 and 5, the rear plate 11A may be formed with longitudinally arranged recesses or channels 36 slotted or open at intervals as at 38. Overlying the slots 38 and extending between and integral with the side walls 37 which define the channels 36, are downwardly-inclined plates or members 39.

It is preferable that the cover 11 should have an aperture 40 in the upper portion, through which is to appear the name of the advertiser, name of product being advertised, or other desired indicia. Preferably also, this aperture should receive a removable plate, say a glass plate 41. For that purpose, a groove or recess 42 is formed into the rear face of the wall, adapted to receive the plate 41, which, for convenience, is rectangular in shape. In order to removably lock the plate in position, spring fingers 43, secured at one end to the wall as with screws 44 and engaging the plate at the other end, are provided, as best shown in Figure 2.

Similarly, it is preferable that the centre plate or glass panel 14 should be removably secured in place, and the rear face of the wall is formed with a groove or recess 46 adapted to receive the glass panel. Spring clips or fingers 47, fixed by screws 47A, may also be used, to removably lock the panel in place.

The cover 12, at the bottom, is formed with an aperture 48 around which is secured a plate 49. This plate is formed with an aperture 50 adapted to receive the bowl of a pipe to be lighted, and a second aperture 51 adapted to receive the end of a cigarette or cigar to be lighted. The lower end of the plate slidably carries a push button 53 adapted to operate the switch 54 which closes the circuit energizing both the electric bulbs 20 and the heating or lighting device 55.

The switch device may be of any suitable design, and as more or less diagrammatically shown in Figure 10, may comprise a casing 56 enclosing two insulated spring contacts 57 and 58 electrically connected to the two leads (not shown) respectively, and normally held out of contact. In the casing is slidably mounted a plunger 59 of suitable insulating material, one end of which projects out of the casing 56. The push button 53 is slidably mounted in the plates 49 and cover 12 and its inner end is threaded to adjustably receive a threaded sleeve or cap 60 of insulating material. A set screw 62 is preferably used to releasably lock the sleeve on the push button rod. The push button device, including a coil spring 53A, is such that the sleeve 60 will normally engage one end of the plunger 59, so that by pressing upon the button, the contact 58 will be deflected and engage the other contact 57, to thus close the electric circuit. This arrangement of switch and push button will enable one to easily and readily remove and replace the cover 12.

The heater or lighter, shown in its entirety as 55, is disposed rearwardly of the apertured plate 49 and conveniently formed, and located,

so as to enable one to light a pipe, cigarette or cigar. The preferred form of the lighter proper is shown in Figures 6 and 7. 66 is a core of insulating material, such as porcelain, the upper end of which is covered with a threaded copper sleeve 67 forming a threaded plug, adapted to be removably received in a correspondingly threaded copper sleeve 68, forming a socket. The socket 68 is moulded or cast in a porcelain (or the like) bracket 70 which may be secured to a bracket 71 fixed to the rear plate 11. One lead of the circuit (not shown) is electrically connected to the socket. The other lead (not shown) of the same circuit is electrically connected to a centre contact or post 73 forming part of the socket, all according to usual practice. In other words, the contact 73 and the sleeve 68 provide the two required contacts of a usual electric socket. The core 66 is preferably tapered from top to bottom and its wall is formed with a spiral groove 74. An electric element 75 is wound around the core, engaging or lodging in the spiral groove, and one end is soldered or otherwise electrically connected to the sleeve 67, while the other end passes up through a longitudinal centre bore or hole 77 in the core, to be similarly connected to a post or contact 78 in the sleeve. Obviously, when the sleeve 67 is screwed into the socket 68, the element is connected in, or forms part of, the electric circuit. A perforated cover or mica cigarette or sleeve 80 is applied around the core 66, to cover or shield the element. The mica sleeve is conveniently protected against damage by providing a metal sleeve 83 terminating at the bottom in an inner ledge or shoulder 85, and at the top, in an enlarged portion or rim 86. The sleeve 83 preferably has a number of vents 85A. The core 66 may be formed with a rim or bead 87. The sleeve or shield 83 is held in operative position, around the heater proper and in engagement with the bead 87 of the core, by means of a split, clamp ring 89, the ring being formed to embrace or encompass both beads 86 and 87. Supported by the shoulder 85 and closing off the lower end of the sleeve 83, is a perforated mica disc 84. In order to gain access to the mica cigarette or shield 80, as when one wants to light a cigarette or a cigar, the wall of the metal sleeve 83 is partly removed to form an aperture 91.

When it is desired to light one's pipe, the bowl is brought up to partially receive the lower end of the metal sleeve 83. It has been found, however, that in order that a pipe may be efficiently lighted, a baffle plate such as will engage the rim of the pipe bowl, should be provided. Accordingly, the lighting device uses a baffle plate 93 which is so mounted as to be capable of a certain movement parallel with the axis of the core 66. Thus, two guide rods 94 are fixed to opposite extensions 93A of the baffle plate 93 and these rods are free to slide in the ends of a cross member 95 secured to the metal sleeve 83. Coil springs 96 encircling the guide rods and tensioned between the baffle plate and the cross member 95 will yieldingly resist the upward movement of the baffle plate relatively to the metal sleeve 83. The downward movement of the baffle plate, on the other hand, is determined by providing nuts 97 threaded on the upper ends of the guide rods. From the baffle plate preferably extends an upwardly-directed sleeve 97A to encircle but clear the sleeve 83.

The construction of the lighting device may be modified. For instance, in Figure 8, the metal

sleeve 83A is shown as being formed with more or less triangularly-shaped, inwardly-bent lugs 100 which are adapted to engage correspondingly formed recesses 101 formed in the upper portion of the core 66A. In such a modification, the clamps 89 are eliminated, and the sleeve 83 and core simplified. Again, the lighting device may be modified, as shown in Figure 9, wherein set screws 102, carried by the metal sleeve 83B engage into holes 103 made into the wall of the core 66B. Again, this modification makes for a simplified construction of sleeve and core.

If desired, the apertures in the plate 49 may be provided with a door 105 in the form of two complementary sections 106, all as best shown in Figures 11 and 12. The sections are pivoted to the inside face of the cover 12A as at 107, and the sections are normally held in closed, co-engaging relationship by means of a tensioned spring 108 anchored at its opposite ends in the sections, respectively. In order to open the door, or more particularly, to swing both sections 106 outwardly, a rounded lug or shoulder 109 is formed intermediate the length of the shank 110 forming part of a switch push button 110A mounted to slide in and through the bottom wall of the cover 12A, and is adapted to slidably engage cam or inclined faces or edges 119 formed in the door sections 106. The member 109 is so formed and sized, and the cam faces so inclined, that a small upward movement of the push button will swing the door sections sufficiently to completely uncover or disclose the pipe aperture 50, and the cigar aperture 51 as well. A nut 111, engaging with the bottom wall of the cover, determines the downward movement of the plunger or shank of the push button. The switch may be made substantially as shown

in Figure 10, including a casing 56A secured to a bracket 115 extending forwardly from the base plate 11A, in which casing are two contacts similar to those shown as 57 and 58 in the said figure. The push button shank 110 slides in the casing, and is pushed upwardly to close the circuit, against the action of a coil spring 118.

I claim:

1. In a lighter device, a casing having an aperture through which a pipe, cigarette or the like may be introduced, a lighting device including an electric element so positioned within said casing that the article to be lighted must be at least partly introduced into said aperture, an electric switch, a plunger operable to close said switch, a pair of door sections spring-held in abutting or closed relationship pivotally mounted adjacent said aperture to close and open the same, and co-operating means on said door sections and plunger operable to open said aperture when said plunger is moved to close said switch.

2. In a lighter device for pipes, an elongated insulated member, an electric element mounted on said member, a sleeve surrounding said element and member fixed relatively to said element and adapted to be received into the bowl of a pipe, a transverse member rigidly mounted on said sleeve, a baffle plate surrounding said sleeve adapted to be engaged by the rim of the pipe, rods between said transverse member and said baffle plate to guide said baffle plate axially of said element, and springs between said transverse member and said baffle plate yieldingly resisting the axial movement of said baffle plate as urged by the pipe when pressed thereagainst.

LESLIE D. JAMIESON.
